UNITED STATES PATENT OFFICE.

JOHN T. MCISAAC, OF EAST WEYMOUTH, MASSACHUSETTS.

SHOE AND INSOLE THEREFOR.

Application filed March 7, 1927. Serial No. 173,267.

My invention aims to provide an improved flexible or arch-supporting shoe and insole therefor.

In the drawings, illustrating by way of example one embodiment of my invention:—

Fig. 1 is a longitudinal, vertical section through the sole and heel portions of a shoe in accordance with one form of my invention, the shoe upper being indicated, in part, 10 in dotted lines;

Fig. 2 is a bottom plan view of a portion of the insole of Fig. 1;

Fig. 3 is a view similar to Fig. 2 of another portion of said insole; and

Fig. 4 is a longitudinal, vertical section through the assembled insole and illustrating the same in a position assumed when the shoe is worn, for example during walking.

While my present invention is applicable 20 to shoes of any type, I have illustrated it in connection with a shoe of the welt type, including (see Fig. 1) a usual or desired upper 1, an outsole 2 stitched to the welt 3, and a heel 4.

Referring more particularly to Figs. 2, 3 and 4, the insole comprises a main or inner section, element, or member 5, seen in Fig. 2, and a supplemental and complementary outer section or element 6, which may in some instances be formed integrally with said main section but is herein illustrated as a separate piece; see Fig. 3. Said main or inner section is preferably of the usual full length and is provided on its lower face around the fore part with a suitable, marginal stitch-receiving formation shown as comprising the parallel ribs or flaps 7, 7 turned up in the known manner from the adjacent face of the insole. Said rib formation, however, instead of continuing rearwardly along the insole in the usual manner to a point adjacent the heel, terminates at approximately mid-length of the main section 5, desirably just forward of the shank portion and along a line 8 which is substantially the rear line of the ball of the sole.

The portion of said main or inner section of the insole to the rear of said line 8 may conveniently be referred to as the shank or rear part 9 of said section, including the shank proper and heel portions. Said shank part 9 is preferably thinned or scarfed at its forward end 10, Fig. 2, along a line substantially parallel or coincident with the line 8 above mentioned. Said inner insole section is thus afforded a marked flexibility in the region of the ball of the foot and particularly in the

vicinity of the weakened area 10, at the junction of the shank with the forepart of the insole.

The supplemental or outer insole element 6, Fig. 3, is shaped and proportioned, desirably substantially as illustrated, to conform to the rear part 9 of the main section. As indicated by the dotted line in Fig. 3, said outer section is scarfed or beveled at the forward edge of its upper face, as at 12, for reception against the thinned end 10 of the main section 5. Along the opposite side edges of its outer face said supplemental section 6 is provided with a stitch-receiving formation similar to that on the main insole section and herein comprising the flaps or ribs 13, 13 which, when the inner and outer sections are assembled, form a continuation of the flaps or ribs 7, 7 upon the inner section, and extend rearwardly substantially to the heel.

In assembling the insole the outer element 6 is placed flatwise against the under face of the rear part 9 of the inner element 5 and, if desired, cemented or otherwise attached thereto over a limited area of the contacting faces at the forward end of the outer element. Preferably, a cork or other filler 14 is inserted between the inner and outer sections of the insole at the shank. A fabric, preferably 80 canvas, or other reinforcing or like element 15, is cemented or otherwise secured to the exposed outer faces of the two insole elements, desirably lying against and reinforcing the inner stitch-receiving flap or rib and coextensive in length therewith. The complete insole thus assembled may then be handled in the usual manner, the shoe upper and lining, together with the welt being secured by a 85 usual inseam to the rib formation of the insole, and the outsole in turn stitched to the welt. A filling 16, Fig. 1, of any suitable material may be provided intermediate the outsole and insole within the ribs 7, 7 and 13, 13. 90

From the foregoing description taken in 100 connection with the drawings, it will be apparent that in the finished shoe the upper and welt are directly secured only to the fore part of the inner insole section 5 from the toe back to the break on the sole, herein at the line 8, while rearwardly thereof the attachment of upper and welt is only to the outer or supplemental section 6 of the insole. At its rear in the vicinity of the heel seat, the supplemental insole section is united to the outsole 6 and to the heel in the usual manner, by nails, as indicated in Fig. 1. At least a major portion of 105 110

the shank of the inner insole section, however, is left free to yield and move relatively to the underlying lower insole section, being separable from the latter.

- 5 The resulting action is substantially as illustrated in Fig. 4. The inner insole section, while free from the outer section, as stated, is confined at the heel by the surrounding counter or heel portion of the upper and, if desired, it may be further secured by adhesive or other attachment to the underlying section 6. When the heel is raised, as in walking, the inner section 5 of the insole, flexing on the shorter radius and being confined only at its ends or end portions, is therefore caused to arch upwardly in the region of the shank, below the instep, substantially in the manner shown in said Fig. 4, and thus affords a flexible and continuing but upwardly pressing arch support of conscious and appreciable degree which makes for comfort and endurance both in standing or in walking.

20 My invention is not limited to the particular embodiment thereof shown and described, its scope being pointed out in the following claims.

I claim:

1. An insole comprising a main element 30 having a fore part adapted for attachment to the shoe upper and welt, and a rear part including shank and heel portions, a second element fitting flatwise against said rear part of the main element and terminating at its 35 forward end substantially in the rear line of the ball of the foot, said main element being scarfed on its lower face to provide a shoulder against which the front edge of said second element abuts, and a fabric reinforce on 40 the lower face of the fore part of said main element and overlapping onto the lower face of said second element, said elements being provided with a marginal rib formation partly on one and partly on the other thereof, 45 whereby the shoe upper and welt may be attached to said second element and to the fore part only of said main element, leaving the rear part of the latter free to flex relatively to the second element.

- 50 2. An insole comprising an element includ-

ing heel, shank, ball and toe portions and having a marginal, stitch-receiving formation on the lower face of said ball and toe portions only, and a second element including only a heel and shank portion, mating 55 with said main element, the latter being recessed on its under face, the forward wall of said recess providing a shoulder to receive any end thrust of said second element and prevent relative forward movement 60 thereof, and having only its forward portion attached thereto, said second element having on the under face of its shank portion a stitch-receiving formation providing a continuation of that on the first element.

3. In an insole, a main section substantially the length of the shoe upper to which it is to be attached, having a stitching rib around the fore part of its under face, the shank portion of said main section being thinned to provide a region of maximum flexibility adjacent its forward end and recessed to form a shoulder on its under face and a separate outer section for said insole substantially co-extensive in area with the rear part of said main section and scarfed at the forward edge of its upper face for reception against said thinned part of the main section and with its forward edge abutting said shoulder, said outer section being provided on its lower face 75 with a stitching rib in continuation of that on said main section.

4. An insole comprising an inner portion 5, a shorter outer portion 6 having its rear edge substantially coinciding with that of said inner portion, said inner portion having a marginal, stitch-receiving formation 7, 7 along that part of its lower face which lies forwardly of said outer portion, and the latter having a similar formation 13, 13 from its 85 forward extremity substantially to the heel, and a layer of fabric 15 overlapping the exposed lower faces of said portions, a shoulder being formed on the lower face of said inner portion 5 along the ball line 8 constituting an abutment for the forward edge of said outer portion 6.

In testimony whereof, I have signed my name to this specification.

JOHN T. McISAAC.
